UNITED STATES PATENT OFFICE.

CHARLES W. LUMMIS, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

FEEDING MECHANISM FOR GAS-PRODUCERS.

1,270,962.

Specification of Letters Patent.

Patented July 2, 1918.

Application filed March 10, 1916. Serial No. 83,396.

To all whom it may concern:

Be it known that I, CHARLES W. LUMMIS, a citizen of the United States, residing at Worcester, in the county of Worcester and 5 Commonwealth of Massachusetts, have invented a certain new and useful Improvement in a Feeding Mechanism for Gas-Producers, of which the following, taken in connection with the accompanying drawings, is 10 a specification.

The present invention relates to feeding mechanism for gas producers, and has particular reference to a mechanism of the above type for mechanically supplying fuel 15 to a producer by the introduction of successive intermittent charges, the mechanism being adjustable to vary the rate at which the charges are introduced and also to vary the size of said charges, in accordance with 20 the rate of consumption of fuel within the producer.

The mechanism belongs in general to that type of feeder set forth and described in my copending companion applications Serial 25 No. 36,626, filed June 28, 1915, and Serial No. 55,551, filed October 12, 1915, the same providing a movable fuel receptacle adapted in one position to receive a charge of fuel from a chute, hopper, or other source of 30 supply, and subsequently to deliver such charge into the combustion chamber of the producer. The devices of said copending applications are characterized by the provision of a cradle or seat in which the fuel 35 receptacle rotates, said seat having a surface which is effective with respect to not more than one half the circumference of said receptacle. The present invention differs from the feeders of said copending applications, 40 however, in the provision of a construction which avoids the necessity for limiting the circumferential extent of the effective seating surface of the receptacle, and yet, at the same time, permits the necessary freedom 45 of movement for said receptacle so that the danger of sticking or binding when the receptacle expands or becomes coated with tar on its surface, is avoided.

The essential features of the present invention are fully set forth in the following description, reference being had to the accompanying drawings, in which—

Figure 1 is a sectional view of a gas pro-

ducer, equipped with fuel feeding means constructed according to this invention.

Fig. 2 is a cross sectional view of the feeding mechanism in a plane at right angles to the section of Fig. 1.

Fig. 3 is a sectional view of the feeding mechanism in the plane of the line 3—3, 60 Fig. 2.

Fig. 4 is an end view of the feeding mechanism.

Like reference characters refer to like parts in the different figures.

Referring to the accompanying drawings, the gas producer shown in Fig. 1 provides a combustion chamber 1 which is inclosed by a stationary cover section 2, the latter being preferably water cooled and having 70 an opening 3 in its top for the entrance of fuel. The opening 3 communicates with the interior of a hollow water cooled shell 4, superposed upon the top of the producer and providing for the support of the fuel 75 feeding mechanism which forms the subject matter of this invention.

The said fuel feeding mechanism consists of an open ended casting or cradle 5 providing a concave seat 6, from which opens 80 downwardly a passage 7 communicating through the shell 4 and opening 3 with the combustion chamber 1. Bolted to each flanged end of the cradle 5 is a plate 8, the said plates 8 providing inclined recesses 9 85 for the reception of adjustable bearing blocks 10, which are supported upon set screws 11, as shown in Fig. 4.

The bearing blocks 10, 10 afford journals for trunnions 14, 14 which project from the 90 ends of a cylindrical drum or receptacle 15. The latter is adapted to rotate in the concave seat 6, between the end plates 8, 8. As shown clearly in Fig. 2, the rigid portion of the concave seat 6 embraces considerably 95 less than one half of the circumference of the drum 15, said rigid portion providing a sealing edge 16 above the axis of rotation of the drum on one side of the passage 7, and said rigid portion on the other side of 100 the passage 7 terminating in a recessed edge 17, for a purpose hereinafter set forth.

This limitation on the circumferential extent of the rigid seating surface 6 leaves the drum free to move away from said seating 105 surface during its rotation, since the cradle

5. does not extend far enough around the drum for the parts ever to bind. In other words, all danger of the drum sticking or binding in the cradle, by expansion or otherwise, is effectively prevented by thus limiting the rigid portion of the seating surface, thereby permitting said drum and its trunnions to move not only rotatively, but also away from said rigid seating surface.
- 10 Movement from said rigid seating surface is limited by means of adjustable set screws 13, 13 carried by plates 12, 12 which project upwardly from the plates 8, 8. These set screws 13, 13 are adapted to bear lightly against the upper ends of the blocks 10, 10 when the drum is in operation. That is, the set screws 13, 13 are set up loosely when the feeding mechanism is cold; after the producer is started, and the parts have 20 heated up and expanded in the normal operation, these set screws allow the drum to assume a position for free rotative movement in the cradle, while at the same time holding it properly to its work. In the 25 event of undue or unusual heating and expansion of the drum, the set screws 13, 13 may be still further slackened off, as will be readily understood. In other words, these set screws perform by their adjustability, the same function, in effect, as a yielding spring or a weight, except that in practice they afford a better means of holding the drum to its work, and thus assist in preventing any accumulation of tar or dirt 30 on the contacting surfaces of the drum or cradle.

A fuel spout 18, leading from a hopper or other source of fuel supply, has suspended therefrom a trough or chute 19, the longitudinal axis of which may be inclined to the perpendicular, with its delivery end disposed adjacent the surface of the drum 15 immediately above the sealing edge 16 of the cradle. The flow of fuel from the spout 18 45 through the chute 19 against the wall of the drum 15 is controlled by a sliding gate 20, which is adjustable up and down to vary the distance of its lower end from the bottom of chute 19, and thereby to vary the effective 50 fuel opening afforded by the delivery end of said chute. The adjustment of the gate 20 is determined by the position of a transverse rod 21, removably carried within an upturned portion of the gate, there being a 55 series of vertically spaced holes 22 in the side walls of said chute to receive the ends of said rod. In this manner the area of the fuel resting by gravity against the surface of the drum, to support the column of fuel contained within the inclined chute 19 and spout 18, is varied.

The drum 15 has a longitudinal opening 23 in its wall; the circumferential extent of this opening is slightly less than the circumferential distance between the sealing edge

16 and the nearest edge of the passage 7. It will be obvious that this opening 23 must be of less width than the effective sealing surface of the seat 6 on opposite sides of the passage 7, since in the rotation of the drum, 70 in the direction of the arrow, Fig. 2, communication between its interior and the interior of the producer must be completely closed before the leading edge of said opening arrives at the delivery end of the chute 75 19. In the same way, the rear edge 24 of said opening must be sealed before the leading edge begins to uncover the passage 7, since otherwise there would be an escape of gas from the combustion chamber 1.

To effect this result, and at the same time to retain the advantage incident to the provision of a rigid seat 6 of limited circumferential extent, as herein shown, means are provided in the form of a segmental sealing 85 plate 25 concentric with said seat and constituting an extension thereof beyond the recessed edge 17. The edge of the plate 25 is seated in the recess of edge 17, and preferably bears against a suitable packing material 26 held in the recess by a retainer 27 to prevent the escape of gas past the joint thus formed. The plate 25 is yieldingly held against the surface of the drum 15 by means of a plurality of springs 28, which are carried upon outwardly projecting rods 29. Said rods 29 extend loosely through openings in a bar 30 which is attached to the plates 8, 8, the springs 28 being thus confined between said bar and the plate 25 and 100 exerting their force to hold said plate at all times against the surface of the drum 15.

By the provision of this non-rigid extension of said seat 6, the sealing of the opening 23 prior to the uncovering of passage 7 is effectively accomplished. At the same time, notwithstanding the fact that the effective sealing surface thus provided embraces more than one-half the circumference of the drum, the danger of sticking or binding, when the 110 drum expands or becomes coated with tar on its surface, is entirely avoided. Should such expansion occur, or should any force having a tendency to raise the drum from the bottom of seat 6 arise, the plate 25 will 115 yield a corresponding amount, and will, moreover, invariably seek a position adapted to maintain a substantially gas tight seal with respect to the opening 23 of the drum. As herein shown, any movement of the drum 120 away from seat 6 follows the inclination of the recesses 9, in order to prevent jamming against the rigid edge 16 of the cradle which, in the present instance, is above the axis of rotation of the drum.

To prevent fuel from being carried out of the chute 19 by the rotation of the drum, a flexible guard, in the form of stiff wire brushes 31 carried upon a bar 32, is provided. Likewise, the present invention contemplates 125

the use of scraping devices for removing tar and coal dust from the surface of the drum and to prevent, as far as possible, the access of foreign matter to the supporting sealing surfaces afforded by the rigid cradle 5 and the yielding plate 25.

The drum may be rotated, either continuously or intermittently, by any suitable mechanism for this purpose. As herein shown, one of the trunnions 14 carries a flanged disk 33, Fig. 1, providing inner and outer peripheral surfaces for engagement by inner and outer friction shoes 34 and 35. Said shoes are caused to operatively engage the disk 33 by the oscillation of a bell crank 36, which is journaled loosely on the trunnion 14 and is actuated through a connecting rod 37 having an adjustable connection 38 with an eccentric 39. Said drum actuating mechanism, which preferably includes a yielding safety connection 40, whereby an undue resistance to the rotation of the drum renders the same inoperative, forms no part of the present invention and hence need not be specifically described.

While I have herein shown the provision of a single yielding member 25, on one side only of the passage 7, it will be apparent that my invention contemplates the provision of more than one such member; obviously, the sealing surfaces on both sides of the passage 7 might be constituted in whole or in part by yielding sections. It will be obvious also that, provided the rigid portion of the cradle be effective over not more than one-half the circumference of the drum, no restraint will be imposed against the movement of the drum away from its seat by said yielding section or sections, it being clear that expansion of the drum, or accumulations of tar or other foreign matter upon its surface, cannot under these conditions hinder its free rotative movement.

The construction herein shown and described, which contemplates a cradle or support providing one or more flexible sections, avoids the necessity for the careful and accurate machining and the fitting of parts which is demanded by the use of a wholly rigid cradle. Moreover, the nicety of adjustment required by feeders of this type, to obtain a substantially gas tight seal, is not essential in the present construction, since the yielding sections are in every respect self-adjusting.

I claim,

1. In a fuel feeding mechanism for gas producers, a rotatable charging member and a seating surface coöperating with said member to form a substantially gas tight seal against the escape of gas from the producer chamber in every position of said member, said surface comprising a section held yieldingly against said member, whereby free movement of said member away

from the remainder of said seating surface is permitted.

2. In a fuel feeding mechanism for gas producers, a rotatable charging member and a seating surface coöperating with said member to form a substantially gas tight seal against the escape of gas from the producer chamber in every position of said member, said surface comprising a rigid section and a yielding section, whereby free movement of said member away from said rigid section is permitted.

3. In a fuel feeding mechanism for gas producers, a rotatable charging member and a seating surface coöperating with said member to form a substantially gas tight seal against the escape of gas from the producer chamber in every position of said member, said surface comprising a rigid section embracing not more than one half the circumference of said member, whereby free movement of said member away from said rigid section is permitted, and a section adapted to adjust itself to the position of said member.

4. In a fuel feeding mechanism for gas producers, a rotatable charging member and a seating surface coöperating with said member to form a substantially gas tight seal against the escape of gas from the producer chamber in every position of said member, said surface comprising a rigid section, a yielding section, and a substantially gas tight joint between said sections, said yielding section permitting free movement of said member away from said rigid section.

5. In a fuel feeding mechanism for gas producers, a rotatable charging member having an opening, a supporting means for said member providing a concave seat with a passage to the producer chamber for registration with said opening, and a sealing surface on each side of said passage, one of said surfaces having a yielding section, whereby free movement of said member away from said seat is permitted.

6. In a fuel feeding mechanism for gas producers, a rotatable charging member having an opening, a supporting means for said member providing a concave seat with a passage to the producer chamber for registration with said opening, said seat embracing more than half the circumference of said member, and means for permitting radial movement of said member within said seat.

7. In a fuel feeding mechanism for gas producers, a rotatable charging member having an opening, a supporting means for said member providing a concave seat with a passage to the producer chamber for registration with said opening, said seat embracing more than half the circumference of said member and coöperating therewith to form a substantially gas tight seal against the es- 130

- cape of gas from the producer chamber in every position of said member, and means for permitting radial movement of said member within said seat.
5. In a fuel feeding mechanism for gas producers, a rotatable charging member, a supporting means therefor providing sealing edges above the axis of rotation of said member, and means for permitting radial movement of said member within said supporting means.
9. In a fuel feeding mechanism for gas
- producers, a rotatable charging member, a supporting means therefor providing sealing edges above the axis of rotation of said member, one of said edges adapted to yield, to permit radial movement of said member, and means for guiding said member, in its radial movement, past the other sealing edge.

Dated this ninth day of March 1916.

CHARLES W. LUMMIS.
